UNITED STATES PATENT OFFICE.

HERMON MOON, OF GROVE CITY, PENNSYLVANIA.

BALANCED SLIDE-VALVE.

SPECIFICATION forming part of Letters Patent No. 450,470, dated April 14, 1891.

Application filed December 15, 1890. Serial No. 374,819. (No model.)

To all whom it may concern:

Be it known that I, HERMON MOON, a citizen of the United States, residing at Grove City, in the county of Mercer and State of Pennsylvania, have invented certain new and useful Improvements in Balanced Slide-Valves, of which the following is a specification, reference being had therein to the accompanying drawings, in which—

10 Figure 1 represents a horizontal sectional view taken on the line $x\ x$ of Fig. 3; Fig. 2, a vertical sectional view taken on the lines $x'\ x'$ of Figs. 1 and 3; Fig. 3, a vertical transverse section on the line $x''\ x''$ of Fig. 1, and 15 Fig. 4 a detail side elevation of the parts of the valve.

The invention relates to certain improvements in balanced slide-valves for reciprocating steam-engines; and it has for its objects 20 essentially to provide for readily starting the engine at a full head of steam and also to take up the wear of the contiguous surfaces of the valve and valve-seat, as will more fully hereinafter appear.

25 Referring to the annexed drawings, a indicates an ordinary steam-cylinder, which has formed integral with it at one side a horizontal cylindrical valve-chest b , provided with the usual heads and stuffing-boxes and communicating with the respective ends of the cylinder by means of the steam-ports $a'\ a'$. The valve-chest is shown as formed integral with the cylinder; but it is evident that it 30 may be formed separate and bolted thereto, if desired. It is also evident that the valve-chest may be formed or located on either side of the cylinder or on top of the same, instead of on the left-hand side of the cylinder, as shown. The live-steam pipe e connects with a 35 steam-passage f , which latter leads into the side of the valve-chest about midway its length. The two exhaust-ports $g\ g$ preferably lead out of the valve-chest at its lower side, one port being near each end. A casing g' is 40 bolted over the exhaust-ports, so as to connect both of them with the exhaust-pipe e' . The valve c snugly fits the interior of the valve-chest and is connected to the usual valve-rod d . Longitudinal grooves $c'\ c'$ are formed in 45 the exterior of the valve from end to end to permit the exhaust-steam to pass freely and continuously around the valve and out at the

exhaust-port, no matter in what position the valve may be. The valve is formed with a horizontal transverse cylindrical recess h , out 55 of the bottom of which leads a transverse slot h'' , which is preferably similar in shape and length to the engine-ports $a'\ a'$ and with which it alternately registers and communicates when in operation. A tube d' is connected to the forward end of the valve and communicates with a recess h in the same, this tube extending out through a stuffing-box in the forward end of the valve-chest a suitable distance and being provided at its end 60 with a chamber d'' , which is provided with a petcock d''' , whereby the condensed steam collected in the valve may be blown off. A section h' of the valve is made movable and provided with a piston-like extension, which 65 is adapted to work truly within the cylindrical recess in the valve and which may be provided with a suitable annular packing to render it steam-tight. The outer surface of this movable section h' is curved to conform to the 70 interior of the valve-chest and to the general contour of the valve. This section may be provided with shoulders c'' near its ends, which abut against similar shoulders formed on the valve, and thereby serve to assist in 75 guiding the section in its movements. The section is kept pressed normally outward against the interior of the valve-chest by a coil-spring interposed between its lower end and the bottom of the recess h , whereby all 80 wear of the contiguous parts of the valve and chest may be readily and automatically compensated for and taken up. A longitudinal groove j is formed in the exterior of the movable section and is of sufficient length to communicate with the steam-inlet throughout the 85 full length of the stroke of the valve, and a steam-passage i connects this groove with the interior of the valve, whereby the valve will 90 always remain full of live steam.

95 The operation will be apparent from the foregoing, and is briefly as follows: When the steam is admitted, it immediately fills the interior of the valve and remains therein ready for immediate access to the cylinder, the pressure of the steam upon the inner end of the movable section serving to assist the spring in keeping the section pressed against the valve-chest. When the valve is moved so that

its outlet-opening h'' registers with one of the steam-ports a' , the steam enters the cylinder and moves the piston in the usual way, the exhaust-steam passing into the valve-chest

5 and out through the exhaust-openings, the side grooves $c' c'$ allowing the steam to pass freely around the valve and make its exit through both exhaust-openings, as is evident.

Having thus described my invention, what

10 I claim is—

1. The combination of a steam-cylinder, a valve-chest connected therewith by the usual ports, a reciprocating valve working in the chest and provided with an interior cylindrical chamber, a steam-port leading out of this chamber and adapted to connect alternately with the steam-ports of the engine, a movable section carried by the valve and adapted to normally press against the interior of the

15 valve-chest and provided with a piston-like extension working in the said cylindrical chamber of the valve, a spring under the said movable section to keep it normally pressed against the interior of the valve-chest, and

20 25 steam-passages formed through the said movable section, as and for the purposes described.

2. The combination of a cylindrical valve-chest provided with inlet and exhaust ports and ports leading to the cylinder, a cylindrical reciprocating valve provided with steam- 30 passages through it connecting the inlet to the cylinder-ports, and a tube connected to the interior of the valve and extended out of the valve-chest and provided with a cock, as and for the purposes described. 35

3. The combination of a valve-chest provided with steam inlet and exhaust ports and ports leading to the cylinder, and a chambered valve adapted to reciprocate therein, this valve being provided with a longitudinal exterior groove serving to continuously connect the exhaust-ports, as and for the purposes described. 40

In testimony whereof I affix my signature in presence of two witnesses.

HERMON MOON.
